UNITED STATES PATENT OFFICE.

BRUNO CRISTIANO, OF CANONSBURG, PENNSYLVANIA.

MOUTHPIECE FOR CORNETS AND SIMILAR INSTRUMENTS.

1,305,691.

Specification of Letters Patent.

Patented June 3, 1919.

Application filed March 12, 1919. Serial No. 282,168.

To all whom it may concern:

Be it known that I, BRUNO CRISTIANO, a subject of the King of Italy, residing at Canonsburg, in the county of Washington 5 and State of Pennsylvania, have invented new and useful Improvements in Mouthpieces for Cornets and Similar Instruments, of which the following is a specification.

My invention relates to mouthpieces for 10 cornets, trombones, alto, tenor, and bass horns, bugles, and the like.

It is the object of my invention to provide a mouthpiece for wind instruments of the types enumerated above, which reinforces 15 and controls the lips so as to hold them firmly in place and enabling the instrument player to execute all notes, particularly those of extremely high pitch, with accuracy and ease. Another object is to provide, for the 20 aforesaid purposes, an attachment for the mouthpieces of said instruments, which may be readily secured thereto and removed therefrom. I provide a number of differently shaped attachments adapted to the 25 particular needs or mouth characteristics of players of the said instruments. If one attachment is not satisfactory, others may be attached to the mouthpiece until a perfectly fitting and satisfactorily operating one is selected.

Referring to the accompanying drawings, which illustrate only a few of the various forms which my invention may assume, Fig. 1 is a side elevation of a cornet mouthpiece 35 embodying my invention; Fig. 2, an end elevation thereof; Fig. 3, a side elevation with parts in longitudinal section; Fig. 4, a side elevation showing a mouthpiece with the lip-engaging attachment omitted, but showing 40 one of the lugs to which such attachment is secured; Fig. 5, an end elevation of a second form of my invention; and Fig. 6, an end elevation of a third form thereof.

Referring first to Figs. 1 to 4, the usual 45 mouthpiece is shown with the stem or shank 1, and the cup, bowl, or bell-shaped portion 2 which receives the central portion of the lips, and has the usual circumferential bead 3 at the outer end or mouth of the bowl.

To opposite sides of the bowl 2 I secure 50 my improved lip-holding members 4 designed to extend toward the corners of the mouth and to engage with the lips at the particular places required by the player, and 55 to conform to his particular mouth and lip structures. The drawings can, therefore,

show only in a general way how the lip-holding members are shaped. I have shown in Figs. 1 to 4 the particular form of my invention which I use, though I use the lip-holding members permanently soldered to the sides of the mouthpiece, which I was 60 able to do after I had determined the precise shape thereof.

Each lip-holding member 4 has the shank 65 5 and the wing 6. The wing extends laterally from a line below the outer or end face of the bead 3 and gradually beyond the place of the open end of the cup 2 to the point 7 which is the extreme portion needing reinforcement toward the corner of the mouth. From the line of the closed lips, that is from the line III—III, Fig. 2, the wings extend 70 laterally to form the extension or ears 8, which shape more or less gradually back 75 toward the edge of the cup as they extend around or partially overlap the bead 3, as shown on Figs. 1 and 3. In Fig. 5, the wings 6' are attached only to narrow portions of the cup as shown at 9, to provide for such 80 lips as would be obstructed by such broad attaching portions as are shown at 10 on Fig. 2. In Fig. 2 the ears 8' extend around farther over the central portions of the lips. In Fig. 6, the wings 6'' have a broader attaching 85 portion 10' than the portion 10 of Fig. 2, and have the ears 8'' extending well around toward the central portion of the lips, while the extreme lateral portions 7' converge more or less gradually toward points. 90

It is essential to the best action of the mouthpiece to have the wings begin their ascent below the end face of the bead 3. In some cases they could arise from the rear edge of the bead, while in other cases they 95 might arise at or near the central portion of the bead.

To adapt my invention to the common mouthpiece, I prefer to attach a lug or block 11 at each side of the cup by means of screws 100 13, but any other practical method of attachment may be used. For specially made mouthpieces, the lugs may be cast integrally with the cups. The shanks 5 of the lip-holding members 4 are removably attached to the 105 lugs 11 by the screws 12.

I claim:

1. In a cup-shaped mouthpiece for wind instruments, a cup, a lug on opposite sides thereof, and a wing carried by each lug, extending 110 forwardly of the cup on a line toward the corners of the mouth and extending

laterally from said line around the cup toward the central portions of the lips.

2. In a cup-shaped mouthpiece for wind instruments, a cup, a lug on opposite sides thereof, and means for detachably securing to each lug any of a plurality of lip-holding members.

3. In a cup-shaped mouthpiece for wind instruments, a cup having a circumferential bead at the mouth thereof, and lip-holding members extending from the cup toward the corners of the mouth and arising from the cup below the end face of the bead.

4. In a cup-shaped mouthpiece for wind instruments, a cup having a circumferential bead at the mouth thereof, and lip-holding members extending from the cup toward the

corners of the mouth and arising from the cup below the end face of the bead and extending gradually beyond the said face of the bead.

5. In a cup-shaped mouthpiece for wind instruments, a cup having a circumferential bead at the mouth thereof, and lip-holding members extending from the cup toward the corners of the mouth and arising from the cup below the end face of the bead and extending gradually beyond the said face of the bead, the wings extending laterally into ears which slope rearwardly toward their free ends.

Signed at Pittsburgh, Pa., this 7th day of March, 1919.

BRUNO CRISTIANO.
